US0D1081519S

(12) **United States Design Patent** (10) **Patent No.:** **US D1,081,519 S**
(45) **Date of Patent:** **** Jul. 1, 2025**

(54) **PASSENGER VEHICLE**

(71) Applicant: **Space Perspective Inc.**, Kennedy Space Center, FL (US)

(72) Inventors: **Taber MacCallum**, Kennedy Space Center, FL (US); **Daniel James Window**, Kennedy Space Center, FL (US); **John Zaniel Maccagnano**, Kennedy Space Center, FL (US); **Ryon Warren**, Kennedy Space Center, FL (US); **Vincent David Julien Bachet**, Kennedy Space Center, FL (US)

(73) Assignee: **Space Perspective Inc.**, Kennedy Space Center, FL (US)

(*) Notice: Patent file contains an affidavit/declaration under 37 CFR 1.130(b).

(**) Term: **15 Years**

(21) Appl. No.: **29/861,570**

(22) Filed: **Nov. 30, 2022**

(51) LOC (15) Cl. **12-07**

(52) U.S. Cl.

USPC **D12/320; D12/319**

(57) **CLAIM**

The ornamental design for a passenger vehicle as shown and described.

DESCRIPTION

FIG. 1 is an isometric view, from the top right, of the passenger vehicle.

FIG. 2 is an isometric view, from the bottom left, of the passenger vehicle.

FIG. 3 is an elevation view from the left side of the passenger vehicle.

FIG. 4 is an elevation view from the right side of the passenger vehicle.

FIG. 5 is an elevation view from the front of the passenger vehicle.

FIG. 6 is an elevation view from the back of the passenger vehicle.

FIG. 7 is a plan view from the top of the passenger vehicle; and,

FIG. 8 is a plan view from the bottom of the passenger vehicle.

The broken lines shown in the drawings depict portions of the passenger vehicle that form no part of the claimed design.

1 Claim, 8 Drawing Sheets
